Primary Examiner — Martie K Holtje*(74) Attorney, Agent, or Firm* — Volpe and Koenig, P.C.(57) CLAIM

The ornamental design for a pet ramp with reflective markings, as shown and described.

DESCRIPTION

FIG. 1 is a top, front perspective view of a pet ramp with reflective markings in accordance with our design;

FIG. 2 is a front elevational view thereof;

FIG. 3 is a rear elevational view thereof;

FIG. 4 is a top plan view thereof;

FIG. 5 is a left side elevational view thereof;

FIG. 6 is a right side elevational view thereof;

FIG. 7 is a bottom view thereof; and,

FIG. 8 is a perspective view showing the pet ramp with reflective markings of FIGS. 1-7 in a folded position.
